UNITED STATES PATENT OFFICE.

JOHN BROWN, OF WENATCHEE, WASHINGTON.

BOX-STAMPING MACHINE.

Application filed May 22, 1923. Serial No. 640,750.

To all whom it may concern:

Be it known that I, JOHN BROWN, a citizen of the United States, residing at Wenatchee, in the county of Chelan and State of Washington, have invented certain new and useful Improvements in Box-Stamping Machines; and I do hereby declare the following to be a full, clear, and exact description of the invention, such as will enable others skilled in the art to which it appertains to make and use the same.

The invention relates to a machine for stamping or branding boxes, crates and like containers for receiving fruit, vegetables and the like for market, whereby the size, grade and variety may be ascertained upon inspection of the box without necessitating a thorough examination or the opening of the same.

20 The invention has for its object the provision of a box stamping machine which is readily adjustable according to the size of the box to be stamped and easily set to indicate the size, grade and variety, said machine being operable either by hand or power as required and best adapted to the particular nature of the work in hand.

25 Other objects and advantages will be apparent and suggest themselves as the nature of the invention is understood.

30 While the drawings illustrate an embodiment of the invention it is to be understood that in adapting the same to meet different conditions and requirements, various changes in the form, proportion and minor details of construction may be resorted to without departing from the nature of the invention.

35 Referring to the accompanying drawings forming a part of the application:

Figure 1 is a front view of a box stamping machine embodying the invention,

Figure 2 is a rear view thereof,

Figure 3 is a side view,

40 Figure 4 is a vertical section on the line 4—4 of Figure 2,

Figure 5 is a longitudinal section on the line 5—5 of Figure 3,

Figure 6 is a plan view,

45 Figure 7 is a detail view of opposite side showing power connection,

Figure 8 is a detail view showing the special stamp,

Figure 9 is a detail view showing the

detents attached to a standard for cooperating with adjacent stamp wheels,

Figure 10 is a fragmentary view of a stamp wheel and the indicator coacting therewith, and

Figure 11 is a sectional detail on the line 60 11—11 of Figure 4.

Corresponding and like parts are referred to in the following description and designated in the several views of the drawings by like reference characters.

The main frame of the machine comprises a base 1 and uprights 2. Slots 3 are formed in the uprights 2 and receive blocks 4 which are adjustable therein by means of long set screws 5. Guide bars 6 are attached to the blocks 4 and are movable therewith. The frame provided with the stamping mechanism is carried by the guide bars 6 and is adjustable therewith and movable independently thereof to admit of the stamping mechanism being advanced to mark the box and retracted to be inked and permit of the next box being placed in proper position to be stamped.

The stamping frame comprises a horizontal member 7 and a plurality of standards 8 and is mounted upon the guide bars 6 to move therewith for vertical adjustment and having an independent movement thereon to provide for forward and backward movement of the stamping mechanism. Stamping wheels 9, 10 and 11 are carried by shafts mounted upon the standards 8 and are provided with type to designate size, grade and variety respectively. The stamping wheels 9 are adjustable to bring any required type in position for printing. The stamping wheels 9 and 10 may be adjusted from one end of the machine by means of hand wheels 12 and 13 which are attached to the outer ends of the respective shafts 9^a and 10^a carrying the stamping wheels 9 and 10. To facilitate the setting of the stamping wheels, indicating matter may be provided on a side thereof corresponding with the several stamps and a pointer 14 is positioned to cooperate therewith so that it may be readily known when the required stamp is in position for printing.

Each of the stamping wheels is provided upon a side with teeth 15 and a detent 16 coacts with the teeth to hold the stamping wheels in the required adjusted position. The numeral 17

designates a special stamp which may be placed in position for printing any desired matter upon the box. This stamp 17 is yieldably mounted, as shown most clearly in Figure 8, and is supported at one end of the stamping frame to move therewith.

The stamping wheel 11 is mounted on a shaft 11^a which telescopes the shafts 10^a and 9^a and is retained in place by a latch 11^b pivoted to a side of one of the standards 8.

A crank shaft 18 is mounted upon the standards 8 and links 19 connect the crank portions thereof to an inking pad 20 which is arranged to supply ink to the stamp in printing position. Arms 21 connect the inking pad 20 with the axis of the stamp wheels thereby insuring movement of the inking pad in a circle concentric with the axis of the stamp wheels, whereby the proper inking of the stamp is assured. The inking pad is preferably formed of two similar sections hingedly connected, a spring 20^a mounted upon the pintle yieldably holding the outer section in given position. Rotation of the crank shaft 18 advances and withdraws the inking pad. When the inking pad 20 is advanced, the printing stamps are inked and when the inking pad is withdrawn clearance is had for the forward movement of the stamping mechanism to mark or brand the box. An arm 22 secured to the crank shaft 18 is connected by means of a link 23 with a lever 24 fulcrumed at 25 to the base 1 of the main frame. Movement of the lever 24 effects a rocking of the crank shaft 18 with the result that the inking pad 20 is oscillated and moved into operative position for inking the stamps and carried out of the way so as not to impede the movement of the stamping mechanism when advancing to mark or brand the boxes. A bail 26 connects the horizontal member 7 of the stamping frame with the lever 24 and in this manner the stamping mechanism is moved forward into position for marking the box and returned to normal position to be inked and to be out of the way so as not to interfere with the proper positioning of the next box to be marked or stamped. The lever 24 may be operated by hand or by power. For operating the machine by power, a shaft 27 mounted upon the main frame is provided with a crank 28 which is connected by means of a link 29 with the lever 24. An arm 30 projecting from the shaft 27 may be connected by means of a rod 31 to a motor, not shown, or other operating part. Retractile springs 32 connect the horizontal member 7 of the stamping frame with the base 1 of the main frame and operate to return the stamping frame to normal position after being moved forward to mark and stamp the box.

What is claimed is:

1. In a stamping machine, a main frame, guides adjustable on the main frame, and a

stamping frame provided with a marking mechanism movable in a horizontal direction for marking an object and mounted independently of the main frame upon said guides and adjustable therewith.

70

2. In a marking machine, a main frame, guides adjustably mounted upon the main frame, means mounted upon the main frame for adjusting said guides and holding the same in the required adjusted position, and a stamping frame provided with a marking mechanism movable in a horizontal direction for marking an object and mounted independently of the main frame upon said guides and adjustable therewith.

75

3. In a stamping machine, a main frame comprising a base and uprights, blocks adjustably mounted upon said uprights, guides secured to said blocks, and a stamping frame mounted upon the guides and adjustable therewith and having a movement independent of the main frame whereby to provide for a forward and backward movement of the stamping mechanism.

80

4. In a stamping machine, a stamping mechanism mounted to receive a forward and backward movement, an inking pad therefor pivotally mounted by said mechanism, a shaft having crank portions operatively connected with the inking pad, and an operating lever having connection with said shaft and with the stamping mechanism to move the latter forwardly and backwardly and the inking pad relatively to the stamping mechanism according to the direction of movement.

90

5. In a stamping machine, a marking means, an inking means movable bodily therewith, a shaft movable with the marking means, an operating means for said shaft, and a crank connection between said shaft and said inking means to move the inking means relatively to the marking means incidental to the said bodily movement.

105

6. In a stamping machine, a main frame, a frame slidable thereon, marking means carried by the second frame, inking means for the marking means carried by the second frame, a shaft carried by the second frame, an operating means connected to said shaft and to the main frame, and a crank connection between said shaft and said inking means.

110

7. In a stamping machine, a horizontally slidable frame, marking means carried by said frame, shaft means on said frame mounting said marking means, an inking means for the marking means movably supported from said shaft means, a shaft carried by said frame, means operable to turn said shaft, and a crank connection between said shaft and said inking means.

120

8. In a stamping machine, a main frame, a frame slidably mounted thereon, shaft means carried by the second mentioned

125

frame, marking means on said shaft means, an inking pad for said marking means, means pivoted on said shaft means and carrying said inking pad, a shaft carried by the second mentioned frame, an operating lever having crank connection with said shaft and being pivoted to the main frame, and a crank connection between said shaft and said inking pad.

9. In a stamping machine, standards, three shafts journaled by said standards, and being in telescopic relation, a marker wheel on each shaft, detent means carried by the standards to secure the marker wheels in

adjusted positions, a pawl and ratchet connection between the innermost shafts and one of the standards, the other shafts having adjusting wheels thereon in relatively close relation, and the marker wheel adjacent to the adjusting wheels having adjustment indicia at a side thereof, and a pointer to co-act with the latter movable by said shaft.

In testimony whereof I affix my signature in presence of two witnesses.

JOHN BROWN.
